CLAIM

The ornamental design for a pair of slippers, as shown and described.

DESCRIPTION

FIG. 1 is a top, heel end, perspective view of a right foot component of a pair of slippers, embodying my new design, the left component has not been shown for ease of illustration;

FIG. 2 is a top plan view thereof;

FIG. 3 is a bottom plan view thereof;

FIG. 4 is a right side elevational view thereof;

FIG. 5 is a left side elevational view thereof;

FIG. 6 is a toe end elevational view thereof; and,

FIG. 7 is a heel end elevational thereof.

The broken lines shown at the end of the solid lines in FIG. 1 represent the bounds of the claimed design while all other broken lines are directed to environment and are for illustrative purposes only; the broken lines form no part of the claimed design.
